(57) **CLAIM**

I claim the ornamental design for a collapsible umbrella rig, as shown and described.

DESCRIPTION

FIG. 1 is a perspective view of the collapsible umbrella rig with an overhead perspective and arms extended;

FIG. 2 is a first side view of the collapsible umbrella rig of FIG. 1 with the arms lowered;

FIG. 3 is a second side view of the collapsible umbrella rig of FIG. 1 with the arms lowered;

FIG. 4 is a third side view of the collapsible umbrella rig of FIG. 1 with the arms lowered;

FIG. 5 is a fourth side view of the collapsible umbrella rig of FIG. 1 with the arms lowered;

FIG. 6 is a top view of the collapsible umbrella rig of FIG. 1 with the arms lowered;

FIG. 7 is a bottom view of the collapsible umbrella rig of FIG. 1 with the arms lowered; and,

FIG. 8 is an environmental side view of the collapsible umbrella rig of FIG. 1 with the arms extended.

The broken lines in the drawings depict non-claimed portions of the collapsible umbrella rig and environmental features which form no part of the claimed design.
